METHOD AND APPARATUS FOR BURNING CEMENT

Eugen Szinger, London, England, assignor to Amalgamated Limestone Corporation Limited, London, England

Application June 4, 1953, Serial No. 359,479

Claims priority, application Great Britain June 10, 1952

13 Claims. (Cl. 263—28)

This invention relates to the burning of cement by forming a granulated mixture of raw cement material and solid fuel into beds on grates in a number of independent containers in which burning takes place simultaneously, the operating cycles being staggered, i. e. at any moment one or more containers are being prepared for burning, others are burning at different stages and yet others are being cooled and discharged. The shape and size of the containers may vary, but in general the useful height, i. e. the height between the grate and the upper edge of the container, should be from two to eight feet, that is to say, the containers are small in relation to large vertical kilns. A plant comprising a number of containers working in this way presents the advantages obtained by burning small charges and yet in effect constitutes a continuous burning plant.

Cement clinkers can be burnt in different ways in such sintering containers. For example, each container can be filled to the top with a mixture of granular cement raw material and solid fuel and then (after ignition of the top of the charge) the contents of the container can be burnt by causing air for combustion to flow from the top downwards. Burning can also take place in a rising air stream, the bottom of the filled container being ignited and the air caused to flow from the bottom upwards.

According to this invention, a rising current of air is used, but instead of the container being initially fully charged each container is continuously or intermittently fed with additional mixture of raw material and fuel as the burning proceeds. The depth of the bed in each container increases as the burning proceeds from the bottom upwards, and the combustion zone during the greater part of the burning is always covered by a thin layer of fresh fuel and raw material. The charge may consist of separate particles or nodules of fuel and raw material, but preferably consists of nodules each composed of a mixture of fuel and raw material.

Although the proportion of fuel to raw material in the mixture may be constant, it is found, however, that a considerable amount of fuel can be saved if this proportion decreases as the burning proceeds from the bottom of the container to the top. The decrease can be effected in two or more steps. The mixture of raw material and fuel may also contain pre-burnt clinker of small size, i. e. material which is sieved out and returned to the mixing plant, and the proportion of this may advantageously also decrease as the burning proceeds in each container.

Preferably the combustion air is pre-heated, say to a temperature of 250 to 300° C., this pre-heating being advantageously effected by drawing the air through the hot contents of the sintering containers in which the burning is complete, so that these are simultaneously cooled.

To start the burning a thin layer of fuel or a mixture of fuel and cement raw material is put on the grate of the container and ignited with the aid of a downdraught. Preferably the bulk of the charge is added continuously to the containers as the burning zone progresses upwards,

2

at a rate such that the burning is nearly complete by the time the container is full.

By means of the invention the burning is more satisfactory than when the containers are filled and then ignited. In particular, the resistance to the passage of air is decreased, so that less power is consumed in setting up the air current, and the burning is more uniform so that the clinker is of better quality. Moreover, moisture expelled from the nodules of raw material does not condense in an upper layer and soften the nodules in it, as sometimes happens when the containers are filled before the burning begins.

Preferably the containers are moved through a closed path in stepwise fashion and in a predetermined time cycle, pausing in each of a number of positions. They may run on rails and be moved by hydraulic pushing mechanisms or other mechanical means. In their various positions the containers may lie beneath fixed hoods and, in the burning and cooling positions, above fixed air chambers. The charging of the bulk of the material to be burnt is then effected through the hoods, conveniently by scraping material off a conveyor.

Fig. 1 is a longitudinal elevation of the entrance half of the kiln and

Fig. 2 is a longitudinal elevation of the exit half of the kiln.

In this plant there are twenty one operating positions, but more than twenty one containers since at any instant some containers are travelling along a rectangular track from a position 21 in which the initial thin layer is charged to a position 1 in which this layer is ignited. The track is indicated by lines 77, and it is convenient to follow the cyclic movement of one container around this track, starting in position 21. The container is empty when it arrives at this position, and first a layer of pre-burnt clinker is charged onto the grate as evenly as possible to a depth of from two to six inches from a hopper 71 through a gate valve 72. This layer serves inter alia to protect the grate. Then small coke or coal is charged onto the clinker layer to the depth necessary for ignition from a hopper 73 through a gate valve 74. The container is now ready for the ignition step and it is pushed by a hydraulic mechanism 66 along the track 77 into the position 1. Thereafter the container is pushed into each of positions 2 to 19 in turn by a hydraulic mechanism 65, and at any time all these positions are occupied.

In position 1 ignition takes place by means of an oil or gas flame produced by means of a burner 35 which is attached to a hood 29. During the ignition process an air stream is drawn through the container from the top downwards by a small blower 36, which is connected with the container by means of a suction chamber 22. The combustion gases drawn off escape into the open through a chimney 48. The fuel layer lying on the clinker layer is ignited and partly burnt during the ignition process. The heat developed is retained to a large extent in the clinker layer, and the top surface of this layer reaches a high temperature and forms a heat reservoir capable of igniting a mixture of fuel and raw material subsequently added to it.

After ignition the container is pushed from position 1 to position 2, and at the same time another container prepared for ignition reaches position 1. In positions 2 to 10 the containers lie beneath hoods 30, 31 and 32 and above air chambers 23, 24 and 25. A supply of nodules of raw cement material and fuel is continuously brought to the containers by an endless belt conveyor 55, and is scraped by scrapers 56 into chutes 57. The nodules fall down these chutes through openings in the kiln hoods into the containers. The nodules are delivered to the belt at such a rate that by the time any container moves out of position 10 it is full or nearly full. It is not necessary to

charge each container with exactly the same amount of nodules, nor to charge exactly the same amount in each position, but the amount charged into the container in each position should be only so much as will keep the fire always covered with a thin layer of fresh nodules. Any material carried by the belt past the container 10 falls down a duct 47 and is returned by a conveyor 46 to the raw material mixing plant.

From the air chambers 23, 24 and 25 pre-heated air is forced through the grate openings in the bases of the containers, and flows first through the clinker layer, which was highly heated in the ignition stage, and completes the burning of any ignition fuel not burnt in the ignition stage. The air then serves for the combustion of the fuel added in the nodules with the raw material. The exhaust gases leaving the containers are discharged to the atmosphere through the hoods 30, 31, 32 and chimneys 49, 50 and 51. By the time the container reaches position 10 it should be full to the top and the burning is nearly complete. As the height of the material column in the containers increases from position 2 onward, the air resistance also increases. This fact is taken into account by making the air pressure in the air chamber 24 greater than that in the chamber 23, and the pressure in the chamber 25 greater than that in the chamber 24. For instance, with a useful height of 4 feet for the container, the pressure in the chamber 23 may be from 2 to 4 inches water gauge, in the chamber 24 from 4 to 6 inches water gauge and in the chamber 25 from 6 to 9 inches water gauge. To enable these different pressures to be produced, the chambers are independently fed with hot air by blowers 37, 38 and 39. This hot air is taken from the last section of the plant and is led to the blowers through a hood 34 and pipe 53. Dust separators 43, 44, 45 are fixed in front of the blowers to protect them. The dust separated is returned to the raw material mixing plant by the conveyor 46.

No more material is added to the containers in positions 11, 12, 13, but the burning proceeds to completion in these positions. The containers are supplied with cold air in these positions by a blower 40 through an air chamber 26, and the exhaust gases pass into a hood 33 and chimney 52, but as their temperature is very high they may, if desired, be used for various purposes, e. g. drying the raw materials.

Although cooling begins in positions 11 to 13, the main part of the cooling takes place in positions 14 to 19. Since the container leaves position 13 completely burnt, no combustion gases escape in positions 14 to 19. Cold air fed to the containers by blowers 41 and 42 through air chambers 27 and 28 passes through the hot contents and cools them and is thereby pre-heated to a high temperature. This is the hot air which is taken to positions 2 to 10. In order to protect the blowers 37 to 39 from too high a temperature an automatic mixing valve 54 is fixed to the pipe 53 for the purpose of adding cold air to the hot air stream if a given maximum temperature is exceeded.

The container leaves position 19 in a cold condition and in position 20 its contents are discharged. This may be done, for example, by pushing each container into a rotary tipper which inverts each container and subsequently restores it to its initial position. The contents of the container are tipped to a coarse sieve 68 through a chute 67. The tipping takes place within a casing 78, which is connected to a dust collector not shown. The large-sized material is properly burnt clinker and is separated on this sieve from the fine-sized, which contains insufficiently burnt material. The large-sized clinker goes from the sieve to a crushing mill 69. The fine material is conveyed to a sieve 70 to be separated again into coarse and finer fractions. The coarser fraction goes to the hopper 71 and forms the clinker for covering the grate, and the finer fraction is returned by a conveyor 75 to the raw material preparation plant to be mixed into the raw material.

The invention is not limited to the method described or the plant shown. In particular fuel may be saved by charging in position 10 raw cement material without any fuel in a layer of thickness from one-half an inch to three inches. The excess heat from the layers underneath serves to burn this thin layer.

Again, instead of supplying a constant mixture of raw material and fuel to the containers in positions 2 to 9, or 2 to 10 as the case may be, two or more separately prepared mixtures may be charged, e. g. on separate conveyors, these mixtures being such that a greater proportion of fuel to raw material is fed to the containers in, say, positions 2 to 5, than in positions 6 to 9.

Although in the plant illustrated, the hot air drawn from the containers in the cooling positions is all taken to positions 2 to 10, some of it may be used for drying cement raw slurry. Alternatively or in addition the hot gases of combustion escaping through the hood 33 may be used for the same purpose. Any of these hot gases may also be employed to generate steam, the steam generator preferably being placed above the containers 11 to 19. When the heat in the gases is utilised in any of these ways additional solid fuel may be charged as a top layer onto the bed in one or more of the positions 11 to 13 so that by its combustion it heats the gases. Such fuel may also be charged as a top layer into each container in one or more of the burning positions for the same purpose of increasing the available heat in the waste gases.

The plant may be varied by substantially varying the number of positions or the general lay-out or both. For instance, the plant may include two parallel tracks on each of which the containers form an uninterrupted row, each container being moved in turn from one track to the other by means of a traversing platform or like device. In this case the containers on the one track may be in the filling and burning positions and on the other one in the cooling positions, but of course various arrangements are possible.

The containers may also run on a circular track and then are preferably connected to each other to form an uninterrupted ring. Since in this case complete inversion of each container for the purpose of discharging its contents would be difficult, the bottoms of the containers may be hinged and the discharge effected by allowing each hinged bottom to rock downwards.

Yet again, other cooling systems than the one illustrated may be employed and the means for discharging the containers continuously or intermittently may be varied.

I claim:

1. A method of burning cement in which a granulated mixture of raw cement material and solid fuel is formed into beds on grates in a number of independent containers in which the burning cycles are staggered, the air flows upwards through each bed, and the containers are continuously or intermittently fed with additional mixtures of raw material and fuel as the burning proceeds, so that the depth of the bed increases as the burning proceeds from the bottom upwards and the combustion zone during the greater part of the burning is always covered by a thin layer of fresh raw material and fuel, the burnt beds of clinker being successively discharged so that cement is produced substantially continuously.

2. A method according to claim 1 in which the burning is started by igniting a thin layer of fuel or a mixture of fuel and cement raw material with the aid of a down draught.

3. A method according to claim 1 in which the bulk of the charge is added continuously to each container as the burning zone progresses upwards at a rate such that the burning is nearly complete by the time the container is full.

4. A method according to claim 1 in which the pressure of the air for combustion supplied to each container

is increased as the burning proceeds from the bottom to the top.

5. A method according to claim 1 in which the air furnished for combustion has been preheated, the pre-heating being effected by drawing the air through the hot contents of other containers in which the burning is complete so that these other containers are simultaneously cooled.

6. A method according to claim 1 in which the proportion of fuel in the granulated mixture decreases from the bottom to the top of each container as the burning proceeds.

7. A method according to claim 6 in which the last part of the raw cement material is fed to each container without any fuel.

8. A method of burning cement which comprises the steps of forming a granulated mixture of raw cement material and solid fuel into a bed on the grate of a container; igniting the mixture; supplying air for combustion from below so that the air flows upwardly through the bed; supplying the container from above with additional mixture of raw cement material and fuel as the burning proceeds, so that the depth of the bed increases as the burning in the container proceeds from the bottom upwardly, the combustion zone during the greater part of the burning always being covered by a thin layer of additional mixture.

9. A method of burning cement which comprises the steps of employing a number of independent containers in which burning takes place simultaneously but in which the operating cycles are staggered; forming a granulated mixture of raw cement material and solid fuel into a bed on the grate of each container; igniting the mixture; supplying air for combustion from below so that the air flows upwardly through the bed in each container; supplying each container from above with additional mixture of raw cement material and fuel as the burning proceeds,

5

so that the depth of the bed increases as the burning in each container proceeds from the bottom upwardly, the combustion zone in each container during the greater part of the burning always being covered by a thin layer of additional mixture.

10. A method according to claim 8 in which the mixture of raw material and fuel fed to the containers also contains pre-burnt clinkers of small size, the proportion of pre-burnt clinker in the mixture being decreased as the burning proceeds in each container.

11. A plant for burning cement comprising, a number of sintering containers arranged to move through a defined path in continuous fashion, and in which containers burning takes place simultaneously but with the operating cycles staggered, means for causing air to flow upwards through each container during the burning, and means for periodically charging raw material and fuel into each container during that part of the cycle in which the burning is taking place so that the depth of the bed in each container increases as the burning proceeds from the bottom upwards.

12. A plant according to claim 11 in which the containers lie beneath fixed hoods in the burning position and the charging of the bulk of the material is effected through the hoods.

13. A plant according to claim 11 in which the containers enter cooling positions and in both the burning and cooling positions lie above fixed air chambers.
